UNITED STATES PATENT OFFICE.

JOHN FORNEY DRAPER, OF PATOKA, ILLINOIS.

BEDSTEAD.

SPECIFICATION forming part of Letters Patent No. 353,125, dated November 23, 1886.

Application filed July 12, 1886. Serial No. 207,801. (No model.)

To all whom it may concern:

Be it known that I, JOHN FORNEY DRAPER, a citizen of the United States, and a resident of Patoka, in the county of Marion and State of Illinois, have invented certain new and useful Improvements in Bedsteads; and I do hereby declare that the following is a full, clear, and exact description of the invention, which will enable others skilled in the art to which it applies to make and use the same, reference being had to the accompanying drawings, which form a part of this specification, and in which—

Figure 1 is a top view of a bedstead provided with my improvement. Fig. 2 is a longitudinal vertical sectional view of the same; and Fig. 3 is a transverse section on line *x x*, Fig. 1.

Similar letters of reference indicate corresponding parts in all the figures.

20 My invention has relation to bedsteads; and it consists in the improved construction and combination of parts of a device with which the sides and ends of the bedstead may be so braced and drawn together that they may not spread, allowing the slats to drop out, as hereinafter more fully described and claimed.

In the accompanying drawings, the letters A A indicate the side rails of the bedstead, and B B are the end pieces. Two longitudinal 30 re-enforcing strips, C C, are secured to the inner sides of the flanges D upon the side rails, upon which the slats rest, at the middles of the said flanges, and two pairs of blocks, E E, are secured upon each flange and re-enforcing 35 cleat, forming a space between them, within which a perforation, F, is formed in the flange. Two cross-pieces, G G, have their stepped ends H resting between the blocks, the said ends having downwardly-projecting pins I fitting 40 in the perforations in the flanges, and the outer sides of these cross-pieces are provided at their middles each with an eye, J, projecting outward. The hooked inner ends of two rods, K K, are hooked into each of these eyes, and the 45 outer hooked and diverging ends of these rods are secured in hooks or eyes L L upon the end pieces of the bedstead, the said hooks or eyes being preferably secured to the inner corners of the posts. The cross-pieces are provided 50 with perforations M M, through which pass headed and screw-threaded bolts or rods N N,

having nuts O O upon their threaded ends, bearing against the outer side of one of the perforated cross-pieces.

It will be seen that by tightening the nuts 55 upon these rods the middles of the cross-pieces will be drawn together, drawing upon the diverging rods, which will draw the four posts together, and the cross-pieces having the pins entering the perforations in the flanges will 60 serve to prevent the side rails from spreading, and in this manner the sides and ends of the bed-frame will be prevented from spreading, preventing the slats from dropping out, and if the frame should spread sufficiently to allow 65 a slat to drop, the longitudinal nutted rods and the diverging rods will prevent the slat from dropping upon the floor, but will support it upon them.

In devices of this kind heretofore used the 70 draw of the tightening-nuts has not been in a direct line with the length of the bed, but has been indirect after first drawing on the side rails. Consequently the draw upon the posts; where the most is needed, has been only limited, while in my improvement the draw is 75 entirely upon the posts, and the side rails are held in place by means of the pins in the ends of the cross-pieces.

Having thus described my invention, I claim 80 and desire to secure by Letters Patent of the United States—

The combination, with a bedstead the side rails of which are provided with longitudinal strips, each of said strips having a hole near 85 each end, of two pairs of blocks secured to each of said strips and to the side rails, a pair of cross-pieces having a pin at each end secured to said side rails between said pairs of blocks, a pair of brace-rods secured to the 90 middle portion of each of said cross-pieces, and to the posts of the bed at that end, and a pair of adjusting rods or bolts connecting said cross-pieces.

In testimony that I claim the foregoing as 95 my own I have hereunto affixed my signature in presence of two witnesses.

JOHN FORNEY DRAPER.
